United States Patent Office.

WILLIAM S. MALLORY, OF BATAVIA, NEW YORK.

Letters Patent No. 74,893, dated February 11, 1868.

IMPROVED RAILROAD-RAIL COUPLING.

The Schedule referred to in these Letters Patent and making part of the same.

TO ALL WHOM IT MAY CONCERN:

Be it known that I, WILLIAM S. MALLORY, of the town of Batavia, in the county of Genesee, and State of New York, have invented a new and improved Rail-Coupling, to couple and support the ends of the rails at the joint, and for some distance each way from the ends; and I do hereby declare that the following is a full and exact description thereof, reference being had to the accompanying drawings, and to the letters of reference marked thereon:

To enable others skilled in the art to make and use my invention, I will proceed to describe its construction and operation.

I make two sections of rails, *a a*, and, for coupling-pieces, two pieces of hard timber, *d d*, three feet long or more, about four by eight inches, resting upon three or more ties or cross-pieces; and made to fit into the hollow of the rail, on both sides of said pieces, so that by changing sides, in case of wear or warping, or any other cause, the same may be turned over or around by changing ends, and thus either side may be adapted to the hollow of the rail, and much more accurately adjusted thereto than it can be with iron splices or chairs. These splices are bolted by a screw-bolt, *g*, Figures 1 and 2, to the tie or cross-piece *b*, upon which the ends of the rails rest, which may either pass entirely through said cross-piece, and be held and tightened from time to time by a nut on the end of said bolt, or it may pass partly through said tie or cross-piece, which will serve as a nut, and the same may be tightened by means of the head of the screw-bolt, and thus the tie or cross-piece will be held suspended, as it were, independent of resting upon the ground, if, by accident or otherwise, the ground should be removed from beneath said cross-piece, and can be tightened up and always held firmly under the ends of the rails, and their upper surfaces kept upon a level. This cross-piece or tie, upon which the ends of the rails rest, and to which the splices or coupling are bolted, may be made of iron, extending across and under the rails, and thus firmly stiffen and steady the superstructure of the track. The splices may be fastened to the cross-piece by means of a bolt, *h*, figs. 1 and 2, which has a slot in the lower end for the key, letter *k*, figs. 1 and 2, and a bolt, *m*, with a slot therein, passing up through a portion of the cross-piece, and so arranged that the key *k* will pass through the slots of both bolts, and key the same, and by means thereof said cross-tie will be held suspended firmly under the ends of the rails, and can be tightened up from time to time by driving the key so as to secure an even upper surface upon the ends of the rails, or the bolt *h* may pass through the cross-piece, and be secured by a key on the under side or on the upper side of the cross-piece, and tightened from time to time. The head of the bolt *h* is made of sufficient length, and sunk into the coupling or splice so as to give strength to the same, and both bolts, *h* and *g*, serve the purpose of a spike in holding the rails to their place, and prevent the spread of the track; and in case of a rail breaking near the end, where they generally fail, by means of the coupling the train will be carried safely over the broken rail. The coupling or splice is spiked to all the other cross-pieces or ties upon which it rests, in the usual manner, and they are secured, in addition, by either iron or wooden keys, placed in mortises in the ties or otherwise on the outside, and bearing against the splice, so that wedges in effect upon one side will closely adjust the splices to the hollow of both rails, as they will, the keys being driven upon one side, draw the tie and tighten the splice upon the other side. I also bed into the cross-piece *b*, on a level with the upper surface thereof, one or more light plates of iron, upon which the ends of the rails shall rest, and prevent the wear of the cross-tie, and still obviate the objection of having an elevated piece of iron under the ends of the rails, and producing more or less concussion in the passage of trains.

By my invention above described, many important advantages are secured. I secure, as near as practicable, an even upper surface of the ends of the rails, as from time to time the cross-piece or tie, upon which they rest, is adjusted and held firmly in position. As the coupling is supported by three or more ties, the rocking motion, caused by the depression of the end of one rail and the elevation of the other, is prevented, thus lessening the great concussion upon the ends of the rails as trains pass over them. Accidents are prevented, which are caused by the breaking of rails, as the length of the coupling will carry the train safely over the broken rail, and the breaking of the web or lower flange of the rail is entirely obviated. An accurate adjustment to and support of the rails is secured much more perfectly than can be done in fitting iron to iron. The pounding of the engines and trains upon irregular and elevated masses of iron at the joints of the rails is avoided, which continually wears

out the rails, increases the draught, endangers their safety, and adds to the discomfort of travelling. The track is prevented from spreading, and a strong support afforded at curves. There is also secured, as near as practicable, the right amount of yielding material in the superstructure of railroads, necessary to the safe and comfortable, and profitable or economical operation thereof. The rails can be removed and replaced without disturbing the coupling.

Having thus described my invention, I claim as follows:

1. I claim the arrangement and combination of the keys *k*, slotted bolts *h* and *m*, and splice pieces *d*, in their relation to the rails of a railroad, in the manner and for the purposes herein described.

2. I also claim the combination of the central splice-piece *b* with its plate, *n*, in combination with the rails *a a*, the same being held in place and position by means of screws *g* and keys and bolts, in the manner and for the purpose herein described.

W. S. MALLORY.
